UNITED STATES PATENT OFFICE.

DANIEL E. SIMPSON, OF SCHENECTADY, NEW YORK, ASSIGNOR TO GENERAL ELECTRIC COMPANY, A CORPORATION OF NEW YORK.

FUSE HOLDER.

Application filed May 28, 1924, Serial No. 716,524. Renewed July 13, 1928.

My invention relates to fuse holders and has for its object the provision of a fuse holder embodying a closed protective casing for the fuse and contact parts.

5 My invention has particular application in installations in which the fuse holder is exposed to moisture or other conditions tending to have a corrosive or otherwise destructive effect on the fuse and contact parts 10 associated with it. In carrying out my invention I provide a casing for the fuse which is provided with a water-tight cover, the contact clips for the fuse being secured to the casing and cover respectively.

15 For a more complete understanding of my invention, reference should be had to the accompanying drawing in which Fig. 1 is a side elevation view of a fuse holder embodying my invention; Fig. 2 is a sectional view taken along the line 2—2 of Fig. 1 looking in the direction of the arrows; while Fig. 3 is a fragmentary side elevation view showing a modified form.

Referring to Figs. 1 and 2 of the drawing, 20 I have shown my invention in one form as being mounted on a suitable support 10 which may be a switchboard panel. The fuse holder comprises a hollow cylindrical receptacle member or body 11 made of a 25 suitable insulating material, such as bakelite. One end of the body 11 is closed; as shown, the left-hand end is closed. The member 11 is mounted in an aperture 12 in the support 10 and is provided with a 30 flange 13 which is seated on the support. It is held in place on the support by means of a tubular member 14, the bore 15 of which is slightly larger than the member 11. This member 14 is slipped over the open end 35 of member 11 and is provided with a square base 16 through which screws 17 extend into the support 10 and hold the member in place thereon. Preferably a gasket 19 is provided between member 14 and the support so as to form a water-tight joint.

40 Mounted on the bottom or end wall 24 of the member 11 is a fuse contact clip or receptacle 25 which is provided with a terminal 26 extending through the wall 24. As 45 shown, the terminal 26 is provided with a head which engages the outside of wall 24 and has its inner end peened over to secure the contact clip in place. The contact clip comprises a plurality of resilient contact 50 arms 27 arranged in the form of a cylinder.

It may conveniently be stamped from a sheet of metal. The contact clip is thus arranged to seize one end of a suitable cartridge type fuse 28 which is inserted endwise into the member 11. For the purpose 60 of assuring good contact, one or more turns of a helical spring 29 are wrapped around the contact projections of the fuse clip near their ends whereby the contacts are pressed inward against the fuse. A helical spring 65 30 is provided in the contact clip 25. This spring is compressed when the fuse is inserted and acts in a direction to force the fuse out. The contact clip 32 for the opposite end of the fuse is carried on a cap or 70 cover 33 which closes the member 14. This cover is provided with an inner cylindrical body 34 of insulating material which fits loosely in the bore of member 14. In the inner end of the insulating body is a recess 75 35 in which the contact clip 32 is secured, for example, by riveting or otherwise securing it to a metallic body 36 which is imbedded in the body of insulating material 34.

The contact clip 32 is similar in form to 80 contact clip 25. Electrically connected to the clip 32 at its base are four oppositely disposed contact arms 37. These contact arms are longer than the contact projections of the clip 32 and extend into the member 14 for a short distance into engagement with a contact ring 39 of suitable electric conducting material which is secured in the outer end of member 11, the member 11 being countersunk to receive the ring 39. 85 This contact ring is secured in place by means of two or more insulated rods 40 and 41 of electrical conducting material which extend lengthwise of member 11 in grooves 90 provided for them in member 11 and 95 through the end wall 24 where the rods are riveted or otherwise secured to a terminal ring 42. Besides securing the rings 39 and 42 to the member 11, the rods form an electrical connection between the two. It will 100 thus be observed that when a fuse is inserted and the cover put in place, as shown in Fig. 2, a circuit is closed from terminal 26 through the fuse, contact arms 37, contact ring 39, and the rods 40 and 41 to the 105 terminal 42.

The cover 33 is seated on a ring 45, made of insulating material which is inserted in the member 14 and suitably secured thereto to form a water-tight joint, for example, by 110

means of varnish or shellac. As shown, the end of member 11 may be formed to provide a shoulder against which an inner ring 45^a of insulating material bears so as to hold 5 the member 11 firmly in its seat in support 10. The opposite end of ring 45^a rests against a shoulder on the interior of member 14. A suitable material for the rings 45 and 45^a is a fabric impregnated with bakelite. 10 As shown, the two rings together form an insulating layer on the interior of member 14 and prevent accidental grounding of the circuit when the fuse is being inserted. The cover is held seated by means of a spring 46 15 acting on a pin 47. The spring and pin are carried on a U-shaped bail member 48 which straddles the member 14 and has its ends pivotally connected thereto, for example, by means of tubular rivets 49 and 50 secured to 20 member 14. When the cover is secured in closed position, the pin 47 is seated in a depression 51 in the center of the cover. The pin then extends axially of the member 14. By swinging member 48 on its pivot axis to 25 one side as shown in dotted lines in Fig. 1, the pin 47 may be moved to disengage the cover. As shown, the outer surface of the cover is substantially semi-spherical in shape and has a radius which is considerably 30 shorter than the radius of the circle described by the inner end of pin 47 so that when member 48 is swung from the dotted to full line position (Fig. 1), the pin is forced outward gradually due to its engagement with the cover whereby spring 46 is 35 compressed. Preferably, a gasket 52 is provided under the cover so as to form a water-tight joint.

In inserting a fuse, the cover 33 is 40 removed and one end of the fuse inserted in clip 32. The contact arms of the clip exert sufficient pressure to hold the fuse so that it may be inserted into the enclosing portion of the holder formed by members 11 and 14 45 by grasping the cover and slipping it in place. The insulating member 34 serves as a guide for the inner end of the fuse whereby it is caused to enter the other fuse clip 25. The member 48 is then swung to closed 50 position. The removal of the fuse is facilitated by the spring 30 which tends to expel the fuse from clip 27 so that the fuse remains in the clip 32 and is removed with the 55 cover. A knob 53 is provided on the end of pin 47. This knob may be used in swinging the member 48 and, if desired, it may be pulled out to retract the pin 47. Apertures 54 and 55 are provided in member 11 through which the gases generated when the 60 fuse blows may escape.

In Fig. 3 I have shown a modified form of clamp or securing means for the cover of the fuse holder. Instead of a spring plunger, a locking lever 56 having a cam 57 is 65 provided on the member 58. By pressing

the lever down as shown in full line position, the cap 59 is clamped tightly in place by the cam 57. When the lever is lifted the cap is released and the member 58 can be 70 swung to one side.

In the application of my invention it is contemplated that the terminals 26 and 42 by means of which the fuse is connected in the electrical circuit to be protected will be 75 behind the panel board 10 and protected by the panel board from moisture, spray, etc. The exposed portion of the fuse holder will be the sealed portion on the opposite side or front of the panel board, this portion being formed by member 14 which tightly engages the panel board and the cover 33 which seals member 14. It will be observed 80 that the fuse while completely protected is at the same time readily accessible.

While I have described my invention as 85 embodied in concrete form and as operating in a specific manner in accordance with the provisions of the patent statutes, it should be understood that I do not limit my invention thereto, since various modifications 90 thereof will suggest themselves to those skilled in the art without departing from the spirit of my invention, the scope of which is set forth in the annexed claims.

What I claim as new and desire to secure 95 by Letters Patent of the United States, is:—

1. A water-tight fuse holder comprising members forming a receptacle for the fuse arranged to be inserted in an aperture in a supporting body, means for securing said receptacle to said body so as to form a water-tight joint therewith, a water-tight cover for said receptacle, fuse clips in said receptacle mounted on said receptacle and cover respectively, and quick releasable means for holding said cover on said receptacle. 100
2. A water-tight fuse holder comprising members forming a receptacle for the fuse arranged to be secured in an aperture in a supporting body and form a water-tight joint therewith, a water-tight cover for said receptacle, fuse clips in said receptacle mounted on said receptacle and cover respectively, and terminals for said fuse clips 110 projecting from said receptacle on the opposite side of said supporting member from said cover. 115
3. A water-tight fuse holder comprising a member providing a cylindrical receptacle for the fuse arranged to be inserted in an aperture in a supporting body, a fuse clip mounted in said receptacle, a second member fitting over said first member and forming a water-tight joint with the supporting body, a cover for said second member forming a water-tight joint therewith, a fuse clip carried by said cover, and releasable means for holding said cover in place. 120
4. A water-tight fuse holder comprising 125 a member providing a cylindrical recepta-

- cle for the fuse arranged to be seated in an aperture in a supporting body, a fuse clip mounted in said receptacle, a second cylindrical member fitting over said first member, therewith, a water-tight cover for said second member provided with a cylindrical portion arranged to be inserted in said second member, contact clips on said receptacle and cover 25 arranged to receive a fuse between them when the cover is in place, electrical terminals projecting from said receptacle on the opposite side of said supporting body from said cover, an electrical connection between 30 one of said terminals and the contact clip on said receptacle, means for establishing an electrical connection between the other terminal and contact clip when the cover is put in place, and quick detachable means 35 for securing the cover including a bail secured to said second member and clamping means carried by said bail.
5. A water-tight fuse holder comprising a member forming a cylindrical receptacle for the fuse arranged to be seated in an aperture in a supporting body, a second cylindrical member fitting over said first member, means 20 for securing said second member to said supporting body to form a water-tight joint
- In witness whereof, I have hereunto set my hand this 27th day of May 1924.

DANIEL E. SIMPSON.
